COMBINATION GARMENT

Ariel M. Le May, Chicago, Ill., assignor to S. H.
Camp & Company, Jackson, Mich., a corpora-
tion of Michigan

Application April 13, 1933, Serial No. 665,894

7 Claims. (Cl. 2-27)

The present invention relates to garments of the combined corset and brassière type in which an inner abdominal supporting belt is employed.

Combination corset and brassière garments of the corselette type are employed where only a limited amount of correction and support is required, being limited to the positioning of the breast, diminishing or reducing the diaphragm and abdomen and the keeping of the hips and waist in proper form. The usual function of this type of garment is to retain the figure in a firm state and to present a smooth foundation that will not mar the contour of the outer garment. When physical condition necessitates the employment of surgical supports, considerable difficulty arises when such supports are employed in combination with corselette garments.

Thus it becomes the primary object of my invention to associate a corselette and abdominal support together in a unitary garment in a manner which obviates any restriction being placed upon the desired functions of each acting independently. Moreover, the resulting garment is provided with a single adjustment for both the corselette and the inner abdominal support which is accomplished without sacrifice of the desired positive supporting of the inner construction and the relative yieldability and freedom of movement characteristic of the outer construction.

Other objects and advantages will become apparent as the description progresses. It is to be understood that I intend to include as part of my invention all such changes and modifications as would be readily apparent to those skilled in the art and fall within the scope of the appended claims and that I do not desire to be limited to the details herein set forth.

In the accompanying drawing an elevational view of my improved garment is shown in an extended condition as viewed from the inner side.

Generally considered my improved garment comprising an outer corselette portion which is distinguishable from prior constructions in that the intermediate and lower rear portions have been provided with adjustably laced sections. Elastic sections are provided at the sides of the garment, preferably coextensive with the rear laced sections. Forward of the elastic side sections is arranged an inner belt construction. Additional elastic sections are incorporated in the belt construction adjacent the point of attachment to the outer garment portion. The inner belt construction is coextensive with the overlying part of the front portion of the outer garment with the result that both the outer garment

and the inner belt are adjusted simultaneously through the single laced adjustment in the rear of the other garment. To assure simultaneous and proportional adjustment of both the inner and outer portions of the garment and to provide the necessary positive support which is essential in surgical supporters, each of the aforementioned elastic sections is bridged by non-elastic sections. These non-elastic sections are preferably located centrally of its elastic section and are aligned with the take-up force applied to the garment by the adjustment of the laced portions. Such construction results in providing the necessary release through the upper and lower portions of the corselette outer garment yet accomplishes a positive supporting by the inner belt and assures a positive simultaneous adjustment of both outer and inner garment portions. It is the latter feature which results in a smooth corselette in all adjustment of the inner belt.

Having reference to the drawing, a combination garment is shown having a front covering portion 1 with a brassière portion 2. The rear 3 of the garment comprising sections 4-5 connected by a continued inelastic section 6 at the top of the garment. Adjacent edges of the sections 4-5 are engaged by lacing 7 extending to buckles and strap arrangements 8 movable in opposite directions along the outer surface of the garment to adjust the garment. Preferably the laced adjustment means employed is similar to that disclosed in the patent to Camp, No. 1,463,252. The straps 9 coacting with the buckles 8 are permanently secured to the outer surface of the garment at 10 forward of the elastic side sections as will be hereinafter described. Inelastic side portions 11 and 12 have inserted therein elastic sections 11' and 12', preferably coextensive with the laced portion of the sections 4-5.

An inner belt 14 for supporting the abdomen is secured at 15 to the outer garment forward of the elastic section 11'. An elastic section 16 is inserted between the point of attachment to the outer garment and the central portion of the belt 14. When in position the belt 14 is secured to by quick attachment means to the belt anchorage 17 secured to the outer garment at 18. This anchorage carries an elastic section 19 which may be identical with the section 16. Quick attachment means at the edges 20 and 21 are employed to secure the outer garment while similar means are attached along the edges 22-23 of the inner belt construction. It is to be understood that the

overlying parts of the inner and outer constructions are substantially coextensive and that it is desirable to have the front portion 1 smoothly superimposed upon the belt 14 in all positions 5 of adjustment of the same. To effect this result, non-elastic sections 24 bridge the elastic sections 11' and 12' while similar sections 25 bridge the elastic sections 16 and 19. It is to be noted that the non-elastic bridging sections are 10 in substantial alignment with the resultant of the take-up force applied to the garment by the adjustment of the strap 9; also such sections are located centrally of the elastic sections to permit release at the upper and lower portion of the 15 garment yet provide a positive supporting action through the region of the inner belt. It is in this respect that applicant differs from the garment disclosed in U. S. Patents Nos. 1,226,308; 1,622,873 and 1,887,486.

20 The comfort and smoothness of my improved garment is accomplished in part by the upper section 6 common to the sections 4—5. This section is provided with a hemmed lower edge 26 carrying an elastic strip 27 which is secured to 25 the adjacent edge of the sections 4—5. When the laced edges are drawn together by movement of the straps 9 in opposite direction, an elastic strip hemmed in the lower edge 26 gathers up any fullness that may result at the lower edge 26 of the 30 section 6. At the same time the upper portion of the section 6 as well as the upper portion of the garment is substantially unaffected by the adjustment of the laced edges with the result that there is no binding or discomfort produced and 35 the freedom of movement characteristic of the corselette garment is unimpaired.

In operation, with the lacing 7 loosened the wearer through quick adjustments secures the overlying portion of the belt 14 to the anchorage 40 17 at the side. The front covering portion 1 is then likewise secured at the side by quick attachments located along the edges 20—21. In position the front covering portion is coextensive with the belt 14. Upon adjustment of the straps 9 in opposite direction, both the central parts of front covering portion 1 and the belt 14 will be positively and simultaneously adjusted through the take-up forces transmitted through the non-elastic sections 45 24—25. It is thus apparent that both the inner and outer construction is under the regulation of a single adjustment and that the front covering portion 1 will always extend smoothly over the belt 14 in all its adjustments.

Having described my invention what I claim as 55 new and desire to cover by Letters Patent is:

1. A combination garment of the class described including an outer covering portion comprising front, side and rear members, said members being inelastic and presenting a continuous inelastic 60 region at the upper part of the garment, said front member being attached to one side member at one edge and detachably secured to the other side member at the other edge, an adjustable laced region extending through the central and lower 65 parts of said rear member, elastic sections inserted in said side members extending through the central and lower parts thereof, a separable inner abdominal supporting belt having its ends anchored to said outer portion forward of said elastic 70 sections, additional elastic sections in said belt adjacent the point of anchorage of each end, inelastic sections centrally bridging the elastic sections in said side member and belt, said front member in position overlying said belt, and strap 75 and buckle means movable in opposite directions

along the outer surface of the rear member coacting with said lacing to simultaneously adjust said outer covering portion and inner belt.

2. A combination garment of the class described including an outer covering portion comprising 5 front, side and rear members, said front member being attached to one side member at one edge and detachably secured to the other side member at the other edge, an adjustable laced region located in said rear member, elastic sections extending through the central and lower part of said side sections, an inner abdominal supporting belt having its ends anchored to said outer portion forward of said elastic sections, additional elastic sections in said belt adjacent the point of 10 anchorage of each end, inelastic sections centrally bridging the elastic sections in said side member and belt, said front member in position overlying said belt, and strap and buckle means movable in opposite directions along the outer 15 surface of the rear member coacting with said lacing to simultaneously adjust said outer covering portion and inner belt.

3. A combination garment of the class described comprising an outer covering portion consisting 25 of a separable front member and a rear member joined by side members, an adjustable laced region located in said rear member, elastic sections inserted in said members, and extending through the central and lower part thereof, a separable 30 inner supporting belt anchored at its ends to the outer portion, additional elastic sections inserted in said belt adjacent the point of anchorage of each end, inelastic sections centrally bridging each of said elastic sections, and means coacting with 35 said laced region for simultaneously imparting a positive take-up force to the outer covering portion and the inner belt through said inelastic sections.

4. A combination garment of the class described comprising an outer covering portion consisting of a separable front member and a rear member joined by side members, an adjustable laced region located in said rear member, a separable 40 inner supporting belt anchored at its ends forward of said laced region to the outer portion, regulable means coacting with said laced region to impart a take-up force centrally of the garment, inelastic sections for transmitting said force to the central part of said outer portion 45 and belt to effect a positive and simultaneous adjustment of the same, and elastic sections located in said outer portion for providing the necessary release above and below said inelastic sections.

5. A combination garment of the class described comprising an outer covering portion consisting of a separable front member and a rear member joined by side members, an adjustable laced region extending through the central and lower part of said rear member, a separable inner supporting belt anchored at its ends forward of said laced region to the outer portion, regulable means coacting with said laced region to 55 impart a take-up force to the garment, elastic sections located in said outer garment extending through the central and lower parts thereof, and inelastic sections bridging said elastic sections for transmitting said force to the central part of said outer portion and belt to effect a positive and 60 simultaneous adjustment of the same.

6. A combination garment of the class described comprising a separable outer covering portion, a separable inner supporting belt fixedly secured at its ends to said covering portion, 65

an adjustable laced region for taking up said covering portion and belt, regulable means co-acting with said laced region to impart a take-up force to the garment, said outer covering portion including elastic sections for providing the necessary release in the upper and lower part of the garment, and inelastic sections for transmitting said force to the belt and the overlying part of the outer portion to effect a positive and simultaneous adjustment of the same.

7. A garment of the character described comprising front and rear members joined by side members, the upper portion of said member de-

fining a continuous inelastic brassière section, spaced laced edges extending through the central and lower portions of said rear member, said upper continuous brassière section being characterized by the fact that it includes an inelastic gusset above said spaced laced edges and an elastic member for gathering in said gusset only at the lower edge thereof directly adjacent said laced edges, the major portion of said gusset being free from the action of said elastic member whereby said brassière section is likewise unaffected.
